SCREW SHELL LIGHT SOCKET WITH
GRIPPING MEANS

Adolph W. Gast, Evanston, Ill.

Application March 27, 1950, Serial No. 152,143

2 Claims. (Cl. 173—358)

1

This invention relates to improvements in screw sockets for electric light bulbs and has for its principal object to provide a simple and economical device of the character described, especially designed to restrain the lamp base from becoming loosened in the socket.

My invention is particularly adapted for use in miniature lamps of the kind employed for lighting Christmas trees.

A very common difficulty encountered in Christmas tree lights is the tendency for the lamps to come loose in their sockets. This is particularly troublesome when the lamps are strung in series so that the loosening of one lamp will extinguish the whole string, making it difficult to determine which particular lamp has become loose, or perhaps whether one has burned out.

Commercial lamp sockets are usually made so that the lamp bases fit loosely therein and, in order to hold the lamp against unscrewing, the base must be screwed down tightly in the socket to force the center terminal on the base firmly against the center contact in the socket. Nevertheless, the lamps often become loose when in use.

Another reason for frequent loosening of the lamps is the fact that the central terminals of lamp sockets and lamp bases are usually relatively flat, and one or both such terminals are usually made of relatively soft metal or solder or the like, so that the engaged terminal surfaces present little resistance against tilting of the bulb in the socket.

A particular object of my invention is to provide a simple form of spring-retaining means readily applicable to sockets of commercial form, for holding the bulb in place in the socket.

A further object of the invention is to provide an improved form of center terminal, co-operating with the spring-retaining means, for holding the lamp bulb from tilting and, therefore, loosening in its socket.

Other objects and advantages of the invention will appear from time to time as the following description proceeds.

The invention may best be understood by reference to the accompanying drawings, in which:

Figure 1 is a side view of a lamp and socket constructed in accordance with my invention, with the surrounding casing for the metallic part of the socket shown in dotted lines;

Figure 2 is an enlarged top plan view of the socket shown in Figure 1 with the lamp and its base removed;

2

Figure 3 is a side view of the socket shown in Figure 2;

Figure 4 is a detailed section taken on line 4—4 of Figure 2;

5 Figure 5 is a detailed view showing the spring-retaining member used with the socket shown in the foregoing figures.

Referring now to details of the embodiment of my invention illustrated in the drawing, an electric light bulb 10, herein shown in tapered form of the kind employed with Christmas tree lights, includes a glass bulb 11 and metallic base 12 threaded in the conventional manner for reception in a threaded metallic shell or socket 13, which may be surrounded as usual by an insulated lamp base, indicated in dotted lines at 14 in Figure 1. The metallic shell 13 includes a generally cylindrical body portion 16 flared at one end as indicated at 17 and closed at the other end by a disc 18 of suitable insulating material having a centrally disposed metallic terminal 19 extending therethrough for engagement with a central terminal (not shown) projecting as usual from the lower end of the lamp base 12. The side wall of body portion 16 is formed with a rolled thread 20 so as to present opposed threaded surfaces surrounding both the interior and exterior of said body portion intermediate its ends. In the form shown, the lower end of the body portion 16 is slightly tapered at 21 and terminates in an annular bead 22 within which the edges of the insulating disc 18 are secured. The socket construction so far described is substantially the same as is now commonly employed with commercial lamp sockets, wherein the cylindrical body portion 16 is formed by machinery from a single piece of metal.

Referring now to the novel features of my invention, I provide a substantially C-shaped spring clip, indicated at 25, preferably made of spring wire, having an approximately semi-circular portion 26 formed to fit in the exterior thread of the body 16 and having inwardly arched gripping portions 27, 27 at the opposite ends thereof, continuous with the semi-circular portion 26. Two elongated slots 28 and 29 are cut through the side wall of the body portion 16 at the base of the thread 20 adjacent the lower end thereof, said slots being disposed to permit the arcuate gripping portions 27, 27 of spring clip 25 to project into the interior of the cylindrical body 16 beyond the inner faces of the threads 20 but in alignment with said thread. As will be seen in Figure 2, the slots 28 and 29 are both disposed toward one side of the socket so that, when the spring clip

25 is seated in the thread around the body 16, the inwardly arched gripping portions 27, 27 extend slightly more than one-half the distance around the body but with their out-turned terminal ends 27a spaced circumferentially from each other a substantial distance to facilitate the application of the spring clip to the body portion without distorting said clip.

The spring clip 25 is normally placed under sufficient clamping tension to be held securely in place when the arcuate friction portions 27, 27 are sprung into engagement in their respective slots 28 and 29 in the body 16, but inward movement of said friction surfaces is limited by engagement of the spring with the ends of said slots. The ends 27a of the spring clip are spaced apart slightly less than the diameter of the body 16, so as to permit the clip to be assembled in place on the latter by moderate radial pressure.

I also provide the center terminal 19 of the 20 socket with an upwardly projecting contact point 30 disposed substantially on the longitudinal axis of the socket, as shown in Figure 4. This contact point is preferably made of relatively hard metal, such as brass or bronze, so that it will penetrate the comparatively soft solder-like metal commonly employed on the central terminals of commercial lamp bases.

The socket 13 is provided as usual with wire connections, herein consisting of one wire conductor 35 soldered to the exterior of the tapered portion 21 of the body 16, and a second wire conductor 36 having a terminal portion soldered within the hollow recess 31 on the exterior of the central metallic terminal 19. The conductors extend through a suitable aperture in the insulated base 14.

The use and operation of the device above described is as follows:

The spring clip 25 is applied to the exterior of the shell body 16 with the arcuate gripping portions 27 of said clip extending through the slots 28 and 29 near the base of the thread under sufficient tension to permit a lamp to be screwed into, or unscrewed from, the socket in the usual manner without excessive torsional effort and without any damage to the threads of the lamp base.

The tension of the gripping members 27, 27 will be exerted on the exterior threaded portion of the lamp base. The arrangement is such that the lamp base will tend to be urged toward the side opposite the two friction members 27, 27 so that the lamp base will be securely held in the socket by friction at three widely-spaced points circumferentially thereof. Accordingly, my invention is adapted for use with lamp bases of conventional or standard threaded form, without any special detents, or other locking members. As the lamp is screwed into the socket, the point 30 on the central terminal 19 of the socket will become partially imbedded in the relatively soft metal in the central terminal of the lamp base.

The lamp base will thus be restrained against tilting in the socket with much greater effectiveness than in present commercial forms of lamp sockets, where the sockets are merely formed with a relatively smooth, button-like central terminal.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a screw socket for electric light bulbs, a shell of generally cylindrical shape open at one end and closed by a contact terminal at the other end, the side wall of said shell being interiorly and exteriorly threaded intermediate its ends, said side wall having two circumferentially spaced apertures along the base of its exterior thread at widely spaced angles to each other, and a substantially C-shaped spring clip extending in an arc of substantially more than 180° and arranged to fit under clamping tension in said exterior thread, said spring having inwardly arched portions near its ends extending inwardly and then outwardly through the apertures in said shell for frictional engagement with the threads of a lamp base when screwed therein.

2. In a screw socket for electric light bulbs, a shell of generally cylindrical shape open at one end and closed by a contact terminal at the other end, the side wall of said shell being interiorly and exteriorly threaded intermediate its ends, said side wall having two circumferentially spaced apertures along the base of its exterior thread at widely spaced angles to each other, and a substantially C-shaped spring clip extending in an arc of substantially more than 180° and arranged to fit under clamping tension in said exterior thread, said spring having inwardly arched portions near its ends extending inwardly and then outwardly through the apertures in said shell for frictional engagement with the threads of a lamp base when screwed therein, and the free ends of said spring clip being spaced apart slightly less than the diameter of said shell to permit said spring clip to be pressed radially into place on said shell.
